LLP; Dave S. Christensen

(57) **CLAIM**

The ornamental design for a window scraper, as shown and described.

DESCRIPTION

FIG. 1 is a front view showing our new design for a window scraper;

FIG. 2 is a rear view of the window scraper shown in FIG. 1;

FIG. 3 is a first side view of the window scraper shown in FIG. 1;

FIG. 4 is a second side view of the window scraper shown in FIG. 1;

FIG. 5 is a top view of the window scraper shown in FIG. 1;

FIG. 6 is a bottom view of the window scraper shown in FIG. 1;

FIG. 7 is a first perspective view of the window scraper shown in FIG. 1;

FIG. 8 is a second perspective view of the window scraper shown in FIG. 1; and,

FIG. 9 is a perspective view of the window scraper shown in FIG. 1 with a cover in a second position exposing an interior blade.

The broken lines in the figures form no part of the claimed design.

1 Claim, 8 Drawing Sheets
